UNITED STATES PATENT OFFICE.

RALF T. TOENSFELDT, OF ST. LOUIS, MISSOURI, ASSIGNOR TO HOLOPHANE GLASS CO., INC., OF NEW YORK, N. Y., A CORPORATION OF NEW JERSEY.

DESIGN FOR A LANTERN.

Application filed March 21, 1923. Serial No. 5,553. Term of patent 14 years.

To all whom it may concern:

Be it known that I, RALF T. TOENSFELDT, a citizen of the United States, residing at St. Louis, in the State of Missouri, have invented a new, original, and ornamental Design for Lanterns, of which the following is a specification, reference being had to the accompanying drawing, forming a part thereof.

The figure is a side elevation of the lantern.

I claim:—

The ornamental design for a lantern, as shown.

RALF T. TOENSFELDT.
